DESIGN FOR A JACKET

J. Leah Asteroff, New York, N. Y.

Application November 20, 1947, Serial No. 142,669

Term of patent 7 years

(Cl. D3—4)

To all whom it may concern:

Be it known that I, J. Leah Asteroff, a citizen of the United States, residing in New York city, in the county of New York and State of New York, have invented a new, original, and ornamental Design for a Jacket, of which the following is a specification, reference being had to the accompanying drawing, forming part thereof.

Fig. 1 is a front view of a jacket showing my design.

Fig. 2 illustrates the jacket shown in Fig. 1 in buttoned position, and

Fig. 3 is the rear view of the jacket shown in Figs. 1 and 2.

I claim:

The ornamental design for a jacket, substantially as shown.

J. LEAH ASTEROFF.
